(57) **CLAIM**

The ornamental design for an automobile tire, as shown and described.

DESCRIPTION

FIG. 1 is a perspective view of the automobile tire according to the present invention, the tread pattern repeating uniformly around the circumference of the tire;

FIG. 2 is a front view thereof;

FIG. 3 is a left side view thereof, the right side being a mirror image; and,

FIG. 4 is an enlarged fragmentary view thereof along the lines 4—4 in FIG. 2.

Broken lines are used to show environmental structure only, and form no part of the claimed design.
